DISPLAY STAND FOR LUGGAGE OR THE LIKE

David Hedaya, Brooklyn, N.Y., assignor to Hedaya and Company, Inc., New York, N.Y.

Filed June 13, 1968, Ser. No. 12,324

Term of patent 14 years

Int. Cl. D6—01

U.S. Cl. D80—10

FIG. 1

FIG. 1 is a front elevational view of the display stand for luggage or the like showing my new design;

FIG. 2 is a right side elevational view, the left side elevational view being a mirror image of the side shown;

FIG. 3 is a top plan view thereof; and

FIG. 4 is another front perspective view thereof.

The broken line representation of pieces of luggage in FIG. 4 are for purposes of illustration only.

I claim:

The ornamental design for a display stand for luggage or the like, as shown and described.
